P. BROWN,
IGNITER,
APPLICATION FILED OCT. 24, 1918.

Patented June 24, 1919.

UNITED STATES PATENT OFFICE.

PHELPS BROWN, OF SPRINGFIELD, MASSACHUSETTS.

IGNITER.

1,307,343.

Specification of Letters Patent. Patented June 24, 1919.

Application filed October 24, 1918. Serial No. 259,530.

To all whom it may concern:

Be it known that I, PHELPS BROWN, a citizen of the United States of America, residing at Springfield, in the county of Hampden 5 and State of Massachusetts, have invented certain new and useful Improvements in Igniters, of which the following is a specification.

This invention relates generally to igniters 10 and more particularly to improvements in igniters of the high speed reciprocatory armature type.

Many examples of igniters of this general type will be found in the prior art. The 15 commercial exploitation of reciprocating igniters has, however, been hampered, and their field of service considerably restricted, owing to the fact that they have, heretofore, been notoriously noisy in operation. The 20 factors, which contribute largely in the production of the noise, are nevertheless desirable since they permit certain advantages in operation, which are otherwise not obtainable, so far as I am aware, by igniters of 25 other types. For example, in reciprocating igniters, an armature is reciprocated to and from a core, as by a cam which forces the armature into engagement with the core and then releases it for movement at high speed 30 away from the core. The latter movement is wholly independent of engine speed and thus the intensity of the spark produced on such movement is not, as in other types of igniters, dependent upon the speed of the engine. 35 This is a very important and advantageous feature of the reciprocating igniter, but the very mechanism, which permits this desirable feature to be obtained, also produces a great deal of undesirable noise due 40 to the impingement of various bodies moving at the high speeds necessary for the efficient generation of current. It has been attempted to eliminate such impingement by the use of sliding contact between the core 45 and armature. It will be seen at once, however, that the rate of change of magnetic flux must of necessity be much less when a sliding contact is employed than when the armature and core are disengaged in an axial 50 direction, assuming like armature driving power and like cross-sectional area of the magnetic circuit.

This invention is concerned, among other things, with, and has for its broad object, the 55 provision of a reciprocating igniter which retains the important advantage as to high

speed actuation of the armature independently of engine speed, and yet obtains this advantage in such a manner that practically all of the noise, which has heretofore characterized igniters of this type, is eliminated. 60

According to another feature of the invention, the relatively movable magnetic members of the igniter, which produce the flux variations, are separable for a predetermined 65 distance by resilient means, and a non-yielding reciprocable element, having a stroke greater than said distance, is provided to effect an engagement of said members, together with means permitting a relative 70 yield between the engaged members and said element for the purpose of absorbing the excess travel of the latter, the last-named means being arranged to oppose the compression of the resilient means. 75

According to another feature of the invention, improved actuating means are provided for moving the armature into and out of engagement with the core, which means includes resilient elements arranged to act in 80 opposition on the armature and a reciprocable element connected to the armature through one of the resilient elements.

According to the last-named feature of the invention, the reciprocable element transmits 85 its force through the stronger of a pair of oppositely acting resilient elements and as the armature is moved toward the core the weaker resilient element becomes gradually compressed. The other resilient element 90 does not become compressed until the armature nears the core, but at such time does become compressed for the purpose of retarding the movement of the armature produced by the reciprocable element. In this retarding movement, the two resilient members, 95 acting oppositely on the armature, equalize one another, and the armature is eventually and gently and firmly engaged with the core. 100

According to another feature of the invention, the stroke of the reciprocable armature actuating element is made greater than the lift of the armature and, after the latter has been seated as described, the excess stroke of the reciprocable element is absorbed by the stronger of the two resilient elements. This results in the creation of an appreciable time interval, during which the armature is seated on the core, and such time interval is desirable in order that the magnetic circuit through the core and armature 110 may become fully established. This ar-

angement also insures that the armature is held tightly seated against the core despite wear in the parts, as in the reciprocable element. Were the latter of a stroke just equal to the lift of the armature, it would not be able to tightly seat the armature after it had become shortened through wear.

According to another feature of the invention, the igniter is of the type wherein the flux from a magnetic source is alternately directed through and shunted away from the generating winding, and this arrangement is characterized by the use of only one armature actuated as described, the shunting being accomplished by a permanent shunt of relatively high reluctance. Although this arrangement results in certain losses, such losses are more than offset by the advantages obtained in increased quietness of operation, and, by employing secondary windings, in addition to the primary windings, sparks, of ample intensity for all practical purposes, may be produced.

According to the last-named feature of the invention, coöperating breaker points are necessary to interrupt the primary circuit when the current therein reaches its maximum value, in order that a current may be induced in the secondary winding. The provision of an interrupter which will automatically operate at the stated time is another feature of the invention.

Other features of the invention will appear in the following description and in the illustrative embodiment of the invention in the accompanying drawings, in which:

Figure 1 is a top plan view of an igniter embodying the invention;

Fig. 2 is an elevational view thereof with certain parts broken away;

Fig. 3 is a cross-sectional view taken on the line 3—3 of Fig. 1;

Figs. 4 and 5 are sectional plan views taken on the lines 4—4 and 5—5, respectively, of Fig. 3; and

Fig. 6 is a diagrammatical view illustrative of the electrical connections of the igniter.

In these drawings, there has been shown one type of igniter with which the invention may be employed and, while the illustrated type is desirable and advantageous (and therefore in a measure preferred), the invention is, nevertheless, independent of the particular igniter structure, as to certain features. Particularly, as to the armature actuating mechanism, the specific igniter structure, hereinafter to be described, is to be taken merely by way of illustrative example of one structure with which the armature actuating mechanism may be advantageously used. Such mechanism is, obviously, equally capable of use with other types of igniters, if desired.

The igniter includes, essentially, a suitable source of magnetic flux, as a permanent

magnet 10; a suitable generating winding, as the coil 11; and a core, as 12, with which an armature, as 13, coöperates to vary the flux through the generating winding. Usually, although not necessarily, a second core 14 and a second coil 15 are provided, as shown, the armature 13 connecting the two cores at one end to complete a magnetic circuit from the source 10. The two coils are suitably connected electrically, as in series, by a wire 16 (Fig. 6). If desired, a secondary winding may be provided, as secondary coils 17 and 18 superimposed on the primary coils 11 and 15, respectively. If the secondary winding is to be employed, the coils 17 and 18 are suitably connected electrically, as in series by a wire 19 (Fig. 6). The supply terminals of the igniter will then be the terminals of the secondary winding, as the wires 20 and 21, one, as the wire 21, being preferably grounded in accordance with the usual custom. The terminals of the primary winding are, when the secondary winding is used, electrically connected, as by wires 22 and 23, to coöperating breaker points 24 and 25 of an interrupter mechanism to be later described, which breaker points are automatically separable when the current in the primary winding reaches its maximum value to induce an electro-motive force in the secondary winding. Preferably, as is usual, a condenser 26 is bridged across the breaker points 24 and 25.

The cores 12 and 14 are preferably provided with upper and right angularly turned extensions 27 and 28 which extend toward one another with their ends in closely adjacent relation, so that a permanent air gap 29 is provided. The source of magnetic flux, as a magnet 10, has one magnetic pole magnetically connected to one core and the other similarly connected to the other core. Such connections are made intermediate the ends of the core, so that the flux from source 10 has two paths, one of constant reluctance through the extensions 27 and 28 and the permanent air gap 29 and the other of variable reluctance through the cores 12 and 14, the armature 13 and the double air gap between the armature and cores. Such last-named air gap becomes zero when the armature and cores contact, and the relative movement of the cores and armature causes the variation in the reluctance of the second-named path. When the armature 13 and cores 12 and 14 are in engagement, the major portion of the flux from source 10 flows through that path which includes the cores and thus the primary generating winding is encircled. When the armature and cores are separated so that the double air gap between them is greater than the permanent air gap 29, the major portion of the flux is shunted away from the cores 12 13c

and 14 and flows through the extensions 27 and 28 and across the permanent air gap 29.

Other means may be provided for accomplishing a shunting of the flux from the generating windings, if desired, and the means, chosen to illustrate the invention, although desirable and in a measure preferred, are not essential for all purposes. Particularly the armature actuating mechanism is generally applicable, even to igniters wherein no shunting of the flux occurs.

Referring now to the detailed mechanical structure of the igniter and the mounting of the several elements described; such structure 15 and the means chosen to assemble such elements may, obviously, be varied in many particulars, and the following description is, therefore, to be taken as merely illustrative. The cores 12 and 14, and their extensions 27 20 and 28, are preferably made up of laminations in the usual manner, as indicated in Fig. 1. At the lower end of each core, a pair of angle-shaped blocks 30 (Fig. 5) partially encompass the laminations of the core, 25 and each block of one pair is connected to the corresponding block of the other pair by a cross-bar 31 of non-magnetic material. The cross-bars, blocks, and laminations of the cores are then clamped together by retaining bolts 32. The coils 11 and 17 are 30 mounted on core 12 above the cross-bar 31, and the coils 15 and 18 are mounted on core 14, also above the cross-bar. Above the coils, the cores 12 and 14 are connected together by 35 one or more magnets 10 (blocks 33 and bolts 34, similar to the blocks and bolts just described, being employed). As shown, two magnets are employed one on each side of the cores although, obviously, as many magnets 40 may be employed as is necessary or desired. The magnets 10 and cross-bars 31 serve to space the cores 12 and 14, one from the other, and to tie them together into an 45 assembled structure, and brackets 35, connected to the blocks 30, serve as a means for supporting this assembled structure from a suitable base frame A. Mounted in the latter is a shaft 36, from which the armature actuating means is operated, as will appear, 50 and such shaft may be driven at any desired speed in the illustrated direction by any suitable means (not shown).

The armature actuating means, with which the present invention is more particularly concerned, will now be described. The armature 13, as shown in Fig. 4, is made up of laminations which are so bent as to afford a central opening to receive a bushing 37. On each side of such bushing, the laminations of the armature are clamped together by suitable means, as the retaining bolts 38, and by this means the bushing is firmly held to the armature. The bushing 37 is slidable 65 vertically in a guide block 39 secured to the described cross-bars 31. The upper end of

the bushing may also, as shown, be arranged to slide in a hole 40 in a member 41 of non-magnetic material suitably secured to any stationary part of the igniter, as the magnets 10, for example. Within the bushing 37 and intermediate its ends is a suitably fixed block 42. A spring 43 acts between the base of hole 40 and the block 42 and tends to force the latter, bushing 37, and the armature 13 downwardly away from the cores 12 and 14. 70 A flat spring 44, the ends of which are supported by frame A, as shown in Fig. 3, limits the downward movement of the armature and serves as a cushion to absorb the shock incident to the sudden arrestation of the rapidly moving armature.

The armature 13 is moved upwardly by a cam 46 on the described drive shaft 36. A cam follower, in the shape of a rod 47, rides on the periphery of cam 46 and is guided by 85 and is slidable in the lower portion of the bushing 37. A spring 48 is interposed between the upper end of rod 47 and the lower face of block 42 and, as shown, the ends of the spring may be connected to both the rod 90 and block so that the former is suspended in the bushing 37. The spring 48 is stronger than the spring 43 so that an upward movement of rod 47 will not at first compress spring 48, but will raise the bushing 37, and 95 thus armature 13, until the latter has been moved nearly into engagement with the cores. The compression of spring 48 may and preferably does continue after the engagement of the armature and core, as will 100 be observed from Fig. 3, which shows the cam to have a greater rise than the lift of armature 13. The cam 46 is constructed with a sharp let-off portion 49, which periodically allows rod 47 to descend under the 105 force of spring 48 and thus allows the bushing 37 to be moved downwardly by spring 43 to carry armature 13 away from the cores. The relative movement of rod 47 and bushing 37 by reason of spring 48 is limited by 110 the degree of expansion of the latter, the rod being preferably, as described, prevented from falling from the bushing. This latter arrangement is important since, as shown in Fig. 3, the rod 47 is thereby prevented from 115 impinging on the heel of cam 46 in its downward flight.

The interrupter mechanism is actuated by some reciprocable part of the igniter, as, for example, armature 13. One breaker point, 120 as 24, is adjustably secured to a bracket 50, suitably secured to and insulated from frame A, and the other, as 25, is carried on one end of a lever 51 pivotally supported intermediate its ends at 52 from frame A. A 125 spring 53 tends to hold the breaker points 24 and 25 in engagement, and they are separable during the downward flight of armature 13 when one of the bolts 38 engages the other arm of lever 51.

The general operation of the igniter will largely appear from the foregoing description. To briefly summarize such operation, it will be seen that with armature 13 in engagement with cores 12 and 14, a magnetic circuit of low reluctance exists through the cores and armature from the magnetic source 10. The other available path for flux to flow from the latter is through the extensions 27 and 28 and the permanent air gap 29, but, since this path is of relatively high reluctance, the major portion of the flux encircles the generating winding on cores 12 and 14. However, after armature 13 has been moved away from the cores, the reluctance of the described shunt path is smaller than that of the path, which includes the cores and armature together with the large double air gap therebetween, and accordingly the major portion of the flux is shunted away from the generating windings. Thus, on movement of the armature away from the cores (which movement is accomplished at high speed), there is a change of flux in the cores 12 and 14, and such change, as is well known, results in the generation of an electro-motive force in the primary coils 11 and 15.

The induction of an electro-motive force in the secondary coils 17 and 18 results when the co-operating breaker points 24 and 25 are separated. This separation should, of course, occur at the time when the current flowing in the primary winding reaches its maximum value. Although the desirability of separating the breaker points at such time is obvious, I have found that the provision of means which will actually effect the desired result at the right time are not so obvious. In reciprocating igniters, there are several factors which have an important bearing on the time when the breaker points should be separated. Various lagging influences exist which tend to defer the time when maximum current exists in the primary winding, so that an interruption of the primary circuit at the time, when apparently the break should occur, does not in fact effect maximum results as to induced electro-motive force in the secondary winding. For one thing, the movement of the armature away from the cores does not result in an immediate cessation of flux as might be expected, and the operation of the interrupter must, therefore, be postponed until the armature has been disengaged from the cores for a predetermined interval. Other factors, such as inductance in the primary winding or lagging by reason of the peculiar shunting means employed, may also contribute toward the creation of an appreciable time interval, during which a separation of the breaker points will not effect the induction of a maximum voltage in the secondary winding. In the present igniter,

the lever 51 has been purposely spaced from its actuating bolt 38 to compensate for the lagging influences, which obtain, and to cause the break to occur with close accuracy at the time when maximum current is flowing in the primary winding.

The operation of the armature actuating means, which constitutes one of the most important features of this invention, will now be described. It will be seen from Fig. 75 that, with the parts in the relative positions illustrated, the end of rod 47 does not engage the heel of cam 46. This is important since the rod 47 cannot impinge on the cam and produce noise. As distinguished from the usual arrangement, wherein the rod and cam are already engaged, the rod is gradually picked up as the cam rotates from the illustrated position, and the engagement of the rod and cam is, thus, largely a sliding engagement and, therefore, quiet. As the cam 46 continues to turn in the illustrated direction, the rod 47 is eventually lifted, and the rising of the rod acting through the stronger spring 48 raises armature 13. The rising movement of the latter is at first substantially proportionate to that of rod 47 since spring 48 does not become at all compressed until spring 43 has been first compressed to a considerable degree. Eventually, however, spring 43 will become compressed to such an extent as to present a resistance equal to that of spring 48, and continued movement of rod 47 upwardly will then compress each spring until the armature 13 engages the cores 12 and 14. Further movement of rod 47 will, of course, compress spring 48 only, the armature 13 being held against further movement by engagement with the cores. As the cam 46 continues to turn, it will eventually ride out from under rod 47, thereby allowing the latter to drop. This results in an expansion of spring 48 to a predetermined and limited extent and an expansion of spring 43, which drives armature 13 rapidly downwardly until it is arrested by the cushion spring 44. The latter is so located as to arrest the armature before the rod 47, which travels with it, can impinge on the cam.

It is particularly to be noted that spring 44 is always engaged with the armature 13. When the latter is engaged with the cores, the spring 44 is under little, if any, tension and is, therefore, readily flexed by the expansion of spring 43. However, as the latter expands and its tension decreases, the tension of spring 44 increases, and thus the latter eventually arrests armature 13. A feature of importance is the constant engagement of the armature 13 with spring 44, and this is particularly advantageous since it eliminates all possibility of a noise producing impingement of the former on the latter.

One of the most important results, obtained by the armature actuating mechanism described, is a gentle, quiet, yet firm, seating of the armature upon its cores. The 5 interposition of the spring 48 between the reciprocable element 47 and armature 13 may be said to absorb some of the motion of the element 47 toward the end of its upward stroke. That is, the full movement of rod 10 47 is not communicated to the armature as it nears the cores, and the result is a gradual decrease in its speed. The armature is brought slowly to rest and is gently laid upon and firmly pressed against the cores. 15 The tendency of the armature to rapidly move into abutment with the cores due to magnetic attraction is resisted by the spring 43. Thus, the usual loud clatter of engagement of armature and core is avoided. The 20 spring 43, of course, opposes the upward force exerted by rod 47 as well as the magnetic pull described, but its opposition is of a yielding nature and is accompanied by a yield in the armature lifting mechanism itself. The spring 48 gradually yields as the opposition from spring 43 increases, and the two springs constantly seek to become balanced. Thus, the one spring constantly tends to push the armature toward the core 25 while the other tends to push it away, the armature for any given vertical position of rod 47 finding a balance between these two springs. A further increment of movement of rod 47 disturbs this balance, rendering 30 necessary a new adjustment between the two opposing factors. Meanwhile, the armature gradually decreases in speed by reason of the compression of spring 48, and its retarded approach coupled with the balancing 35 action of the opposed springs results in the armature being engaged with the cores with practically no noise.

It has already been pointed out that the rod 47 is effectually prevented from impingement on cam 46 and that the downward flight of armature 13 is yieldingly arrested by the resilient cushion spring 44. Thus, the movement of the armature on its high speed stroke is effectually quieted as 50 well as on its other stroke.

Another most important feature of the armature actuating mechanism consists in the arrangement whereby the armature lifting member has a greater travel than the 55 armature itself. This is important since it is definitely insured that the armature will be tightly held to the cores even after parts (as the cam 46, rod 47, and so forth) have become worn. Were the yielding connection 60 48 omitted, it will be apparent that an original perfect seating of the armature on its cores would soon be destroyed by reason of wear. Not only this, but the seating of the armature is momentary, and disengagement 65 is liable to occur before the magnetic circuit

has become fully established. The present arrangement is characterized in that, not only is compensation provided for necessary wear in the actuating mechanism, but a definite time interval is created during which 70 the armature is held tightly seated on its cores to insure the full establishment of the magnetic circuit prior to disengagement of the armature.

The described method of slowly seating 75 the armature on its cores is most desirable for, as pointed out, the seating may be quietly effected. However, another advantageous feature is obtained by reason of the peculiar manner of seating the armature. 80 The possibility of a relatively small and undesired spark being produced on the upward movement of the armature is entirely eliminated by the retardation of the armature at the end of its upward stroke. 85

Thus, I have provided an igniter which is characterized, among other things, by improved means for actuating the armature at high speed yet quietly despite the repeated engagement of metallic armature and cores. 90

The invention has been disclosed herein in one embodiment for illustrative purposes, but the scope of the invention is defined by the appended claims rather than by the foregoing description. 95

What I claim is—

1. In an igniter, relatively separable magnetic members coöperating with one another to vary the reluctance of a magnetic circuit, means to move one of said members toward the other, compressible means to move the one member away from the other, said first-named means having a travel greater than the distance of separation of said members, and resilient means to absorb the excess travel of said first-named means, said resilient means opposing the compression of the second-named means. 100

2. In an igniter, relatively separable magnetic members coöperating with one another 110 to vary the reluctance of a magnetic circuit, means to move one of said members toward the other, compressible means to move the one member away from the other, said first-named means having a travel greater than 115 the distance of separation of said members and including resilient means to absorb the excess travel of said first-named means, said resilient means opposing the compression of the second-named means. 120

3. In an igniter, relatively movable magnetic members coöperating with each other to vary the reluctance of a magnetic circuit, resilient means to separate said members a predetermined distance, a non-yielding reciprocable element by means of which said members are moved into engagement, said element having a stroke in excess of said distance, and resilient means permitting a relative yield between the engaged members and 130

said element, said last-named resilient means opposing the compression of the first-named resilient means.

4. In an igniter, relatively movable magnetic members coöperating with each other to vary the reluctance of a magnetic circuit, means to move one of said members toward the other and release it for subsequent movement at high speed away from the latter, 10 driving means compressible by the first-named means to effect the high speed movement, and a cushioning means engaging the movable member and opposing the action of said driving means, the tension of the cushioning means increasing as that of the driving means diminishes on said high speed movement to yieldingly arrest the movable member.

5. In an igniter, having relatively movable magnetic members coöperating with one another to vary the reluctance of a magnetic circuit, means to move one of said members to and from the other member including cushioning means to yieldingly arrest one member in its movement toward the other member and cause the former to be gently seated on the latter.

6. In an igniter, having relatively movable magnetic members coöperating with each other to vary the reluctance of a magnetic circuit, means to move one member into engagement with the other and to subsequently release it for high speed movement away from the latter member, means compressible on the first-named movement to effect the high speed movement when the movable member is released, and a yielding connection associated with the first-named means and compressible as said members approach one another to gradually arrest the relatively movable member and cause it to be gently deposited and yet firmly pressed against the relatively stationary member.

7. In an igniter, having relatively movable magnetic members coöperating with each other to vary the reluctance of a magnetic circuit, means to move one member toward and into engagement with the other member, said means including a yieldable device through which its force is transmitted to the relatively movable member, and means acting in conjunction with the first-named means to cause said device to become compressed as the relatively movable member approaches the relatively stationary member, whereby said members may be gently engaged with one another.

8. In an igniter, having relatively movable magnetic members coöperating with each other to vary the reluctance of a magnetic circuit, means to move one member into engagement with the other and to subsequently release it for high speed movement away from the latter member, said means including a rotary cam and a reciprocable ele-

ment to ride on the periphery of the cam, a cushioning stop constantly engaged with the movable member to yieldingly arrest the relatively movable member in its flight away from the other member and to prevent said element from impinging against said cam when released for said high speed movement.

9. In an igniter, having relatively movable magnetic members coöperating with each other to vary the reluctance of a magnetic circuit, means to move one member toward and into engagement with the other including a reciprocable element and a spring interposed between the latter and the movable member, and means to move the latter away from the other element including a spring arranged to be compressed as the members approach each other and subsequently expand as the movable member is released by the first-named means, said first-named spring arranged to be compressed only after the second spring has been compressed and as the movable member nears the other member, whereby the two members may be gently brought into engagement.

10. An igniter, comprising, a source of magnetic flux, means including a coöperating core and movable armature to provide a magnetic circuit from said source, primary and secondary generating windings associated with said core, coöperating breaker points to which the terminals of the primary winding are electrically connected, said armature being movable away from said core to increase the reluctance of said circuit, means providing a shunt path for the flux with a permanent air gap therein, so that the reluctance of such path is greater than the minimum and less than the maximum reluctance of said circuit, and means to separate said breaker points during its movement away from said core.

11. An igniter, comprising a source of magnetic flux, means including a coöperating core and movable armature to provide a magnetic circuit from said source, means to disengage said core and armature and move the latter a predetermined distance away from the former to decrease the flux in said circuit, primary and secondary generating windings associated with said core, coöperating breaker points to which the terminals of the primary winding are electrically connected, and means to separate said breaker points after said armature has been disengaged from said core and before it has traveled said distance.

12. An igniter, comprising, a source of magnetic flux, means including a coöperating core and movable armature to provide a magnetic circuit from said source, means to disengage said core and armature and move the latter a predetermined distance away from the former to decrease the flux in said circuit, primary and secondary generat-

ing windings associated with said core, cooperating breaker points to which the terminals of the primary winding are electrically connected, and means to separate 5 said breaker points after said armature has been disengaged from said core and before it has traveled said distance, said last-named means arranged to hold the breaker points in separated relation for a predetermined time interval.

13. In an igniter, relatively separable magnetic members coöperating with one another to vary the reluctance of a magnetic circuit, resilient means tending when stressed 15 to separate said members, means to move the members toward and into engagement with one another and thereby place said resilient means under stress to subsequently separate said members, said second named 20 means having a travel greater than the distance of separation of said members, and a second resilient means tending when stressed to move the members toward one another in opposition to the first resilient means, said 25 second resilient means being less readily stressed than the first resilient means and arranged to be gradually placed under stress as the members approach one another to retard the movement of the movable member 30 relatively to that of said second named means.

14. In an igniter, relatively movable magnetic members coöperating with one another to vary the reluctance of a magnetic 35 circuit, a spring acting on the movable member and tending when stressed to separate

it from the other member, a second spring less readily stressed than the first named spring and acting on the movable member in opposition to the first named spring, and 40 means to move the movable member toward and into engagement with the other member, said last-named means having a movement greater than the distance of separation of said members and transmitting its 45 force to the movable member through the second named spring.

15. In an igniter, having a source of magnetic flux, means including a core and coöperating armature to provide a magnetic 50 circuit from said source, means to disengage the armature and move it a predetermined distance away from said core to interrupt the magnetic circuit, primary and secondary generating windings associated with 55 said core, and coöperating breaker points electrically connected to the terminals of the primary winding, a fixed support for one of said breaker points, a movable member to which the other breaker point is attached, 60 yieldable means acting on the movable member and tending to hold said points in engagement, and a part connected with the armature and partaking of its movement, said movable member having a portion located in the path of said part but spaced from the latter when said core and armature are engaged, whereby the breaker points are separated after the disengagement of the 65 armature and core.

PHELPS BROWN.
